UNITED STATES PATENT OFFICE.

THEODORE R. CHASE, OF DETROIT, MICHIGAN.

COMBINED WATER HEATER AND CIRCULATOR.

SPECIFICATION forming part of Letters Patent No. 366,074, dated July 5, 1887.

Application filed April 17, 1886. Serial No. 199,172. (No model.)

To all whom it may concern:

Be it known that I, THEODORE R. CHASE, a citizen of the United States, residing at Detroit, in the county of Wayne and State of Michigan, have invented certain new and useful Improvements in a Combined Water Heater and Circulator; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention consists in certain new and useful improvements in the construction of a water heater and circulator, whereby a more complete distribution of the water is had, furnishing also a better heating capacity, and by 20 my present construction and attachment of the coiled heating-pipe within the boiler I am enabled to locate a feed-door for fuel in the body of the boiler or shell below the coiled heating-pipes, thus dispensing with the common practice 25 of putting the fuel in at the top end of the boiler. I also employ an auxiliary chamber having water-connection with the boiler, being also connected with the coiled heating-pipe within the boiler. From said chamber pass the 30 heating or distributing pipes, which may pass to a room or apartment and be returned to the boiler, or pass through several rooms before returning to the boiler.

Heretofore the common practice has been to 35 lead but one pipe from the boiler to various rooms, or all rooms to be heated, before returning it to the boiler; but by the use of the auxiliary chamber I am enabled to use a series of pipes having an independent connection 40 and heating capacity, which will allow me to cut off the flow of hot water from any room or apartment not desired to be warmed. I also employ a set of auxiliary feed-pipes connecting the auxiliary chamber with the boiler, to 45 give said chamber a large feeding capacity for the various distributing-pipes leading from said chamber.

The important elements of my invention will be hereinafter set forth, and pointed out in 50 the claims.

In the drawings forming a part of this specification, Figure 1 is a central longitudinal section of an upright boiler (shown in perspective) containing my invention. Fig. 2 is an enlarged top plan of the boiler, showing two coils of pipe located therein, one coil being located within the other.

In the drawings, B is the boiler, which consists of an inner and outer shell, S S', in which W W represent the head-rings, through which the rivets pass, and G is the water-chamber, all of which parts are common.

c is a sleeve or pipe, which I screw into the inner shell of the boiler just below the upper head or ring W. Said sleeve is screw-threaded 65 at both ends.

P is a pipe, one end of which I attach to the sleeve c by means of the thimble t, which is provided with an internal right and left hand thread. One end of the thimble screws over 70 the sleeve, the other over the pipe P, thus making a tight coupling. The pipe P from this point of attachment is bent and extends downward centrally in the boiler, the lower point terminating on a horizontal line with the 75 top of the door D of the boiler. It is then formed into a small coil, passing around the vertical portion. Each succeeding coil is formed larger than the one below it, the last coil terminating near the top of the boiler, the 80 diameter of the top coil being nearly equal to that of the inner shell of the boiler. The free end of the coil passes over the top of the boiler through the outer shell, and by couplings e z is attached to the auxiliary chamber C. 85 By the enlargement of each succeeding coil from the bottom one upward each coil is exposed directly to the heat arising from the fire-grates g, whereby the water passing from the boiler B through the coils is rapidly 90 heated before it passes into the chamber C. The chamber C is made of metal and is watertight. I attach to the outer shell, S', of the boiler a series of auxiliary pipes, n, by means of elbows e and couplings a, which also couple 95 said pipes with the chamber C. By this arrangement I draw the hot water from the top of the boiler into the chamber in addition to the flow of water through the pipe P. I locate in the pipes n a cut-off plug, v, whereby 100

the flow of water from the boiler B into the chamber C may be regulated as required.

F F are hot-water-distributing pipes which lead from the chamber C to the room or apartment to be heated. One of said pipes is returned to the boiler B and enters the outer shell at the bottom, as shown at R. The other pipe enters the boiler in a like manner, as shown by dotted lines at R'. The water returning to the boiler in a cooled condition, enters the same around the fire-pit, where it becomes rapidly heated, and as it passes through the coil of pipes P it is again subjected to an intense heat before it passes out into the chamber C. When it is desired to cut off the flow of water from a room, the cut-off valve is turned in the pipe leading to the apartment.

Any number of discharge-pipes F may be connected with the chamber, according to the number of rooms or space to be heated, and in such a case the auxiliary pipes n n assist in supplying the demand upon the chamber C. I also design using two or more coiled pipes P, arranged one coil within the other. In

Fig. 2 P P' represent two of such coils and manner of attaching to the boiler. These coils may be connected to one auxiliary chamber, or each coil may be independently connected to a chamber, having independent distributing-pipes.

A' represents the apron or chute upon which the fuel-door D closes. Through said door the coal or fuel is passed to the grates.

A is the ash-pit, which is provided with a door for the removal of the ashes.

I have shown and described the auxiliary chamber C located outside of the boiler. I design in certain cases to locate it in the top end of the boiler directly over the coiled pipe P, and connect said pipe with the chamber. The auxiliary pipes n n are connected to the chamber, and lead from the inner wall or shell of the boiler B. By locating the chamber in this position it is entirely out of sight and is kept

warm by the current of heat passing up over 45 it, which will prevent the cooling of the water in it, as would be more liable when located outside the boiler. The locating of the feed-door D in the side of the boiler instead of the top, as is common, allows me to locate the chamber C at this point. The upper end of the boiler is provided with the common cover or hood, from the center of which the smoke-pipe arises.

Having thus fully set forth my invention, 55 what I claim as new, and desire to secure by Letters Patent, is—

1. In combination with a boiler having an inner and an outer shell with water-space between them, and the auxiliary chamber C, the coiled pipe P, having one end opening through the inner shell only into the boiler and the other end communicating with said chamber, the auxiliary pipes n n, and a circulating pipe or pipes leading from the chamber C and returning to the boiler and entering the outer shell only of the boiler at or near the bottom, 65 and for the purposes set forth.

2. In combination with a boiler having an inner and an outer shell with water-space between them, and an auxiliary chamber, a series of coiled pipes, as P P', one end of each pipe opening through the inner shell only of the boiler into the water-space thereof, and their other ends communicating with said auxiliary chamber, the auxiliary pipes connecting the boiler to the chamber C and having the cut-off v, and distributing-pipes leading from said chamber and returning to the water-space of the boiler through the outer shell 75 thereof, having cut-off X, substantially as specified.

In testimony whereof I affix my signature in presence of two witnesses.

THEODORE R. CHASE.
